CLAIM

The ornamental design for a reclinable armchair, as shown and described.

DESCRIPTION

FIG. 1 is a front elevational view of a reclinable armchair, showing my new design;

FIG. 2 is a front and side perspective view thereof;

FIG. 3 is a front and side perspective view thereof, in a reclined position;

FIG. 4 is a side elevational view, taken from the left of FIG. 1, the side elevational view from the right of FIG. 1 being the mirror image thereof;

FIG. 5 is a side elevational view, taken from the left of FIG. 1, in a reclined position, the side elevational view from the right of FIG. 1 being the mirror image thereof;

FIG. 6 is a rear and side perspective view thereof;

FIG. 7 is a rear elevational view thereof; and,

FIG. 8 is a top plan view thereof.
